ARTICLE TIMING MECHANISM FOR
PACKAGING MACHINES

Julian A. Dieter, Cincinnati, Ohio, assignor to R. A. Jones & Company, Inc., Covington, Ky., a corporation of Kentucky

Filed July 5, 1962, Ser. No. 207,725
15 Claims. (Cl. 198—34)

This invention relates generally to packaging machines and is directed particularly to a timing mechanism for transferring articles from a processing machine, such as a pouch filler, to a carton loading machine in time with the operating cycles thereof. Upon advancement to the carton loading machine, the articles or pouches are inserted into individual cartons which are subsequently closed and discharged from the cartoning machine, ready for shipment and retail sale.

One of the primary objectives of the invention has been to provide a timing apparatus which is adapted to receive the articles, such as envelopes or pouches issuing from a processing machine at irregular spacing, to space the articles uniformly, and to advance the articles to the buckets of a cartoning machine conveyor in time with the advancement of the buckets, thereby to load the successive conveyor buckets in a rapid, reliable manner.

In the present disclosure, which has been selected to illustrate the principles of the invention, the timing mechanism coacts with a filling machine of conventional design which loads individual pouches with a granulated material, such as dehydrated soup mix; however, it will be understood that the timing apparatus may be utilized with machines for processing other articles. The granulated material is loaded into envelopes or pouches which are formed of pliable sheet material, such as plastic, the pouches being sealed after the filling operation is completed. After the filling and sealing operation, the filled pouches are fed to a check weigher arranged to eject pouches which may be over or under the predetermined weight limits. After passing across the check weigher, which includes a conveyor, the filled pouches are transferred to the timing mechanism of the present invention. The timing apparatus, in turn, is arranged to space the individual pouches with respect to one another and to advance the pouches to the buckets of the cartoning machine conveyor in time with the advancement of the buckets so that each bucket is properly filled with one or more pouches as it advances toward the cartoning machine.

In the present disclosure, two pouch filling mechanisms, associated check weighers and timing mechanisms are utilized to advance the filled pouches to the bucket conveyor for cartoning. Each pouch filling machine is driven by its own individual electric motor independently of the timing mechanism, cartoning machine and associated bucket conveyor. These motors are adjusted to cause the filling machines to deliver pouches one by one at a rate which corresponds, to the operating cycles of the cartoning machine, in terms of the number of pouches which are filled and discharged during a given period of time. However, the filled pouches are delivered to the timing apparatus in a somewhat random fashion because of the operation of the associated check weigher and because of certain inherent characteristics of the pouch filling machine itself. The timing mechanism of this invention therefore operates to compensate for the temporary variations between the output of filled pouches issuing from the check weigher in relation to the operating cycles of the cartoning machine.

The cartoning machine, which is conventional, is adapted to erect individual cartons from a collapsed state, to shift the articles from the conveyor buckets endwise into an open end of the erected carton, to close or seal

2

the flaps of the carton, then to discharge the completed package to a delivery conveyor. A modern cartoning machine of this type is capable of filling the cartons in this manner at relatively high rate of speed. In the present example, the two pouch fillers and associated timing mechanisms are spaced apart from one another along the bucket conveyor and are arranged to load alternate buckets of the cartoning machine conveyor. In other words, the downstream timing mechanism loads the articles into alternate buckets and the empty buckets are loaded as they advance along the upstream timing mechanism, such that each bucket is filled as it advances into the cartoning machine. Each timing mechanism feeds two superposed pouches into the designated buckets, such that two pouches are inserted into each carton upon reaching the cartoning machine. It will be understood however, that the apparatus may be arranged to feed a single pouch into each carton or to feed more than two pouches in each carton, utilizing the operating principles of this invention.

Described generally, each timing mechanism of this invention comprises a timing conveyor having a pair of spaced parallel belts communicating with the conveyor of the check weighing apparatus with an overhead hold-back conveyor disposed above belts of the timing conveyor and arranged to engage the leading edge of the pouches on the belt conveyor. The timing belt conveyor is advanced at a higher linear speed than the hold-back conveyor, which includes downwardly depending hold-back fingers adapted to engage the leading edge of the spaced pouches resting on the belts of the timing conveyor so as to advance the pouches at properly spaced intervals toward the bucket conveyor.

Upon reaching the delivery end of the hold-back conveyor, the packages are transferred to an infeed conveyor, which includes upwardly projecting pusher fingers which engage the trailing edge of the individual pouches to advance them at properly spaced intervals toward the dead plate of a sweep mechanism mounted above the bucket conveyor. The sweep mechanism includes paddles or fingers moving in unison with the buckets of the conveyor and arranged to pass across the dead plate, thereby to engage and transfer the pouches from the sweep mechanism into the buckets in time with their advancement.

Another objective of the invention has been to provide a photoelectric control apparatus operating in response to the advance of the pouches to space the pouches uniformly as they are advanced at random from the check weighing apparatus to the timing conveyor and its associated hold-back conveyor.

Described briefly, each pouch filling machine includes its own photoelectric control apparatus. Each apparatus comprises a pair of photoelectric cells spaced longitudinally above the spaced belts of the timing conveyor and spaced downstream from the overhead hold-back conveyor to act in response to the pouches as they are issued at random from the check weigher. Mounted below the conveyor belts are spaced lamps which project light beams upwardly between the belts to the overhead photoelectric cells. The arrangement is such that the light beams are interrupted in sequence by the individual pouches as they issue from the check weigher conveyor at normal spacing along the belts of the timer conveyor toward the hold-back fingers. The photoelectric apparatus includes an arresting element mounted relative to the belts of the timer conveyor downstream from the hold-back fingers and arranged to temporarily arrest any pouch which is spaced too closely to a leading pouch, or any pouch which is in overlapping relationship with a leading pouch.

For operating the arresting element, the photoelectric cells are interconnected in a control circuit which is arranged to activate the arresting device in the event that both light beams are interrupted concurrently by a pair

of pouches which advance along the timing conveyor at less than normal spacing or in an overlapping relationship, as noted above. Upon being activated, the arresting element temporarily restrains the trailing pouch, then releases it when the normal spacing is re-established, such that the pouches advance to the hold-back conveyor in spaced relationship corresponding generally to the spacing of the hold-back fingers. The spacing of the hold-back fingers is substantially greater than the length of the individual pouches, the arrangement being such that the pouches are accelerated by the belts of the timer conveyor after passing the photoelectric apparatus, so as to be intercepted by the slower moving hold-back fingers as they pass downwardly about an idler sprocket and fall into a stopping position with respect to the path of advancement of the pouches.

A further objective of the invention has been to provide a hold-back conveyor which is adapted to compensate automatically in the event that a pouch is advanced by the belts of the timing conveyor beyond the photoelectric apparatus in improperly timed relationship with respect to the fingers of one hold-back conveyor.

According to this aspect of the invention, the pouches advancing along the belts of the timing conveyor, after having passed the photoelectric apparatus, will be positioned somewhat behind the hold-back finger and somewhat ahead of the next finger. However, in the event of a malfunction in which a given pouch would arrive at the hold-back finger somewhat late, then this finger, in moving around the sprocket of the downstream end of the hold-back conveyor, normally would engage the top surface of the pouch and puncture it. However, to avoid this, the hold-back fingers are pivotally mounted with respect to the chain which advances them. Therefore, when such a condition occurs, the finger falls against and rests upon the top surface of the improperly timed pouch, then pivots upwardly relative to the chain, allowing the late arriving pouch to be advanced by the faster belts of the timing conveyor forwardly to the next finger ahead without any damage to the pouch and without disrupting the timing of the apparatus.

The various other features and advantages of the present invention will be more clearly apparent to those skilled in the art from the following detailed description, taken in conjunction with the drawings.

In the drawings:

charge portion of the infeed conveyor in relation to the bucket conveyor of the cartoning machine.

FIGURE 8 is a cross sectional view taken along the line 8—8 of FIGURE 7, detailing the infeed conveyor structure.

FIGURE 9 is a cross sectional view, taken along the line 9—9 of FIGURE 2, detailing the hold-back conveyor and its relationship to the pusher-type infeed conveyor which advances the pouches to the cartoning machine conveyor.

FIGURE 10 is a diagrammatic top plan view showing the driving system which interconnects the several components of the timing apparatus with the bucket conveyor of the cartoning machine for timed operation.

FIGURES 11 and 12 are diagrammatic views illustrating the action of the hold-back conveyor with respect to a pouch which is improperly timed.

FIGURES 13—15 are diagrammatic views illustrating the operation of the photoelectric control system with respect to a pair of filled pouches which advance toward the hold-back conveyor in overlapping relationship, whereby the trailing pouch is arrested then released in time with the advancement of the hold-back conveyor fingers.

FIGURES 16 and 17 are similar diagrammatic views, showing the operation of the photoelectric control system with respect to a pair of pouches, wherein the two pouches are advanced at a spacing which is less than the minimum spacing, as distinguished from the overlapping condition shown in FIGURES 13—15.

FIGURE 18 is a diagrammatic view, illustrating in a general way, the electrical and air pressure control system of the photoelectric timing apparatus.

General Arrangement

As noted earlier, the pouch timing apparatus of this invention is intended to receive pouches as they are processed by the pouch filling machines and to deliver the filled pouches to the bucket conveyor of the cartoning machine in properly timed sequence. It will be understood that the pouch filling machines are power-driven independently of the cartoning machine and independently of one another. Thus, the timing apparatus compensates for temporary variations between the output of the pouch filling machines and the rate of advancement of the bucket conveyor of the cartoning machine.

According to the example selected to illustrate the principles of the invention (FIGURE 1), the cartoning machine is arranged to insert two filled pouches in each carton. For this operation, two pouch filling machines and associated pouch timers are located along the bucket conveyor downstream from the cartoning machine. As viewed in FIGURE 1, the downstream pouch filling machine is indicated generally at 1 and the upstream filling machine is indicated at 2. Each filling machine 1 and 2 includes an individual pouch timing apparatus, indicated generally at 3, which communicates with the buckets 4 of the cartoning machine conveyor 5. These buckets advance the filled pairs of pouches to the cartoning machine 6, as noted above. The cartoning machine 6 is conventional and is arranged to insert the superposed pouches into respective cartons, to close the cartons, then to advance the cartons to a delivery conveyor 7 ready to be packed into cases for delivery to the wholesaler or retailer.

It will be understood at this point, that the pouch or article timing apparatus 3 of this invention may be utilized with arrangements other than that shown in FIGURE 1. For example, if a single pouch is to be packed into each carton, then a single filling machine and associated timing apparatus may be mounted to communicate with the bucket conveyor 5. On the other hand, if more than two pouches are to be packaged, then a corresponding number of pouch fillers and timers may be em-

ployed, utilizing the same operating principles outlined above.

In the arrangement illustrated, each alternate bucket 4 of the cartoning conveyor 5 receives two superposed pouches 8 (FIGURE 5) from the downstream filling and timing apparatus 1. The alternate empty buckets, upon advancing past the upstream pouch filling and timing apparatus 2, each receive a second pair of superposed pouches. As described later, the delivery end of each pouch timing apparatus 3 includes a sweep mechanism which receives the two superposed pouches, then sweeps the two pouches into the advancing buckets 4.

It will be understood at this point that, in the present example, the cartoning machine 6 is provided with a sensing apparatus (not shown) which checks each conveyor bucket 4. In the event of temporary failure of one or both of the pouch filling machines 1 and 2 or associated timing apparatus 3, the sensing apparatus conditions the cartoning machine to feed cartons only in relation to the buckets which contain pouches. In this manner, the cartoning machine continues to package the pouches issuing from the operative pouch filling and timing apparatus, while remaining inactive with respect to the empty buckets. As soon as the inactive apparatus is again placed in operation, the cartoning machine, through its sensing apparatus, resumes normal operation.

The pouch filling machines 1 and 2 are conventional and for this reason are not disclosed in detail. Briefly, each pouch filler is arranged to feed granulated material, such as dehydrated soup mix or a similar product into a relatively flat rectangular pouch 8 (FIGURE 5) and to deliver the pouches in sealed condition ready for use. The pouch filler are driven independently of the bucket conveyor 5 by individual motors 10-10, as shown in FIGURE 1.

Both filling machines 1 and 2 include a respective delivery conveyor 11 leading to respective weight checking machines 12 and 13. The check weighing machines are also conventional, each including a suitable scale (not shown) arranged to check the weight of the filled pouches and mechanism to eject any pouch which may weigh more or less than a predetermined amount.

In the example shown in FIGURE 1, the filled pouches issuing from the downstream pouch filler 1 are transported by its conveyor 11 directly to the check weigher 12 and to the timer 3, as indicated by the arrows. The pouches which issue from the upstream filling machine 2 are advanced by a similar conveyor 11 to the check weigher 13. However, in this case, the pouches pass from the check weigher 13 to a turntable 14 which advances the pouches through a half-turn, then delivers them to the timing apparatus 3. The turntable 14 is utilized simply to conserve floor space in the layout illustrated in FIGURE 1.

Each timing apparatus 3 includes a pusher type, infeed conveyor, indicated generally at 15 which is arranged to advance the individual pouches from the timing apparatus toward the bucket conveyor 5. In other words, the timing apparatus of each pouch filler segregates and times the individual pouches relative to the associated infeed conveyor 15. The infeed conveyor, in turn, advances the pouches to an associated sweep mechanism which subsequently feeds them to the conveyor buckets 4 in time with the advancement of the buckets, as explained later in detail.

It will be understood at this point, that the motors 10-10 are arranged to drive the pouch filling mechanisms 1 and 2 at speeds which are related to the operating cycles of the carton machine 6. Thus, if the pouches are to be packaged two to a carton, as noted above, then each timing apparatus is arranged to advance two pouches to alternate buckets 4 of the conveyor 5. Thus, the first pair of pouches are fed into a first bucket by the downstream apparatus 1, the second bucket is skipped, and the third bucket is loaded by the downstream apparatus 1.

The alternate empty buckets are then filled as they advance past the upstream apparatus 2. Thus each bucket contains a pair of superposed pouches after it passes both infeed conveyors 15 and enters the cartoning machine. As noted earlier, the timing apparatus of the invention may be utilized in various combinations and speeds other than that illustrated to load a selected number of articles into each carton, utilizing the same operating principles.

Although the pouch filling machines 1 and 2 may be driven by their respective motors 10 at rates which correspond with the rate of operation of the cartoning machine 6, in terms of units handled in a driven time period, nevertheless, it is necessary to time the advancement of the filled pouches accurately with respect to the advancing buckets 4 of the cartoning machine conveyor 5. For this purpose, as explained later in detail, the pouch timing mechanisms 3-3, their associated infeed conveyors 15-15, and sweep mechanisms are in driving connection with the bucket conveyor 5 so that these components operate in synchronism with one another.

As explained later in detail (FIGURE 1), each infeed conveyor 15 leads to a dead plate 16 mounted above the bucket conveyor 5 and forming a part of a sweep mechanism, indicated generally at 17. Each infeed conveyor 25 is arranged to feed two pouches sequentially to the dead plate 16 to form the pair of superposed pouches; the sweep mechanism 17 is timed to sweep the pair of pouches into the appropriate conveyor buckets. The sweep mechanisms 17 are driven by the common driving system in time with the other components of the machine, as noted earlier.

Briefly therefore, the pouch timing mechanisms 3-3 correct any irregularity in the spacing of the pouches issuing from the pouch filling machines 1 and 2, then the infeed pusher conveyors 15-15, also operating in time with conveyor 5, advance the individual pouches to the dead plates 16-16. The pouches dwell momentarily in superposed pairs on the dead plates, then they are transferred by the sweep mechanisms 17-17 into the advancing buckets 4 of the conveyor 5.

Common Driving System

As viewed in FIGURE 1, the cartoning machine 6 is driven by a main motor indicated at 18. This motor 45 includes a drive shaft 20, extending parallel with the bucket conveyor 5 and including driving connections for operating the pouch timing mechanisms 3-3, the infeed pusher conveyors 15, and the sweep mechanisms 17 in time with the conveyor 5, and in time with the cartoning machine, as described below. In other words, all components of the installation shown in FIGURE 1 are driven in time with one another and with the cartoning machine by the drive shaft 20, except the pouch filling machines 1 and 2, which are driven by their own motors 55 10-10, as noted earlier.

The driving system is shown diagrammatically in FIGURE 10, in relation to the timing apparatus of the downstream pouch filler apparatus 1. It will be understood that the driving system for the upstream timing apparatus 60 2 is identical, and that the following description applies to both mechanisms.

Referring to FIGURE 10, the downstream end of the common drive shaft 20 (which parallels the bucket conveyor 5) includes a bevel gear 21 meshing with a bevel gear 22, which is keyed to a cross shaft 23 (FIGURE 2) arranged to drive the sweep mechanism 17. For this purpose, the cross shaft 23 (FIGURES 2 and 7) is journaled in the frame 24 and includes a sprocket 25 on its end opposite the bevel gear 22. The sprocket 25 drives a sprocket chain 26 which is trained about a companion sprocket 27 keyed to a cross shaft 28. The cross shaft 28 is also journaled in the frame 24 and forms a part of the sweep mechanism 17 which transfers the filled pouches 8 into the buckets 4 of conveyor 5, as described in detail later.

As detailed in FIGURE 7, the sweep mechanism 17, which is driven by cross shaft 28, includes sweep fingers 30 which depends downwardly and pass across the dead plate 16 which receives the pouches 8 as they are advanced from the timing mechanism by the pusher conveyor 15. The sweep fingers, by operation of the driving system and main drive shaft 20, advance at the same rate and in time with the buckets 4 of conveyor 5 to push respective pairs of pouches 8 from the dead plate into the buckets. The structural details of the sweep mechanism are described later.

In order to drive the infeed pusher conveyor 15 in time with the other components, main drive shaft 20 (FIGURE 10) further includes a drive sprocket 31 located along the side of the pusher conveyor 15 opposite the bevel gear 21. As shown in FIGURE 2, a sprocket chain 32 interconnects the drive sprocket 31 with a driven sprocket 33 mounted on a cross shaft 34 which is journaled in the frame 35 of the infeed pusher conveyor 15. As shown in FIGURES 7 and 8, the cross shaft 34 includes a sprocket 36 driving a sprocket chain 37 which includes spaced pairs of pusher fingers 38-38. These fingers engage the trailing edge of the respective pouches 8, as indicated in broken lines, so as to advance the pouches to the dead plate 16 in time with the advancement of the sweep fingers 30. The structural details of the pusher conveyor 15 are also described in detail later.

Each timing apparatus 3 includes a belt-type conveyor, indicated generally at 40 (FIGURE 10), which co-operates with an overhead hold-back conveyor 41 in timing the pouches. The belt conveyor 40 and hold-back conveyor 41 (FIGURES 5 and 6), in cooperation with the photoelectric control system, as explained later, space the pouches accurately relative to one another as they issue from the check weigher 13, which includes a suitable belt conveyor (not shown). As noted earlier, the pouches issue somewhat at random from the check weigher and are properly timed by operation of the belt conveyor 40 and hold-back conveyor 41.

As shown in FIGURES 5 and 9 the hold-back conveyor 41 is provided with spaced hold-back fingers 42 which project downwardly between the spaced belts of the belt conveyor 40. The belt conveyor 40 advances at a rate slightly greater than the hold-back fingers, such that the pouches 8, which rest upon the belt conveyor 40 are restrained by the hold-back fingers as they advance through the timing mechanism 3.

In order to advance the belt conveyor 40 and hold-back conveyor 41 at related rates and in time with the other machine components, the cross shaft 34 (FIGURES 7, 9 and 10) of the pusher conveyor 15 includes a drive sprocket 43 for driving the belt conveyor 40 and hold-back conveyor 41. Sprocket 43 drives a sprocket chain 44 trained about a driven sprocket 45 which is mounted upon a cross shaft 46. Cross shaft 46 is journaled in the frame 47 of the belt conveyor 40, which forms a continuation of the frame 35 of the pusher conveyor 15. The belts of the conveyor 40 are trained about pulleys which are keyed to the cross shaft 46, as explained later.

The hold-back conveyor 41 is driven in time with the belt conveyor 40 by means of a driving gear 48 (FIGURES 2 and 9), which is keyed to the cross shaft 46 on the side opposite the sprocket 45. Driving gear 48 meshes with a driven gear 50 which is keyed to a cross shaft 51 forming a part of the hold-back conveyor 41. Cross shaft 51 is journaled in bearing plates 52-52 which project upwardly from the frame 47 of the belt conveyor 40.

In summary with reference to FIGURE 10, the main drive shaft 20 is in driving connection with the sweep mechanism 17 by way of the bevel gears 21 and 22 and is also in driving connection with the pusher conveyor 15 by way of the sprocket 31, chain 32 and sprocket 33. A driving connection is also established from the pusher conveyor 15 to the belt conveyor 40 by means of the

sprocket 43, chain 44 and sprocket 45. From sprocket 45, a driving connection is also established with the hold-back conveyor 41 by the gears 48 and 50 which mesh with one another as shown in FIGURE 9 to drive the cross shaft 51 of the hold-back conveyor.

In order to clarify the driving system, the hold-back conveyor 41 is shown displaced laterally from the belt conveyor 40 in FIGURE 10, the meshing engagement of the gears 48 and 50 being indicated in this view by the broken lines 53. It will be understood that the driving system is arranged to advance the belt conveyor 40 at a rate slightly faster than the hold-back conveyor 41, so that the pouches (which rest upon the advancing belt) are restrained by the hold-back fingers 42 and advanced at proper spacing to the sweep mechanism 17.

Pouch Timing Conveyor System

Referring to FIGURES 3-6, each timing apparatus 3 essentially comprises the belt conveyor 40, the hold-back conveyor 41, and the pouch arresting device, which is indicated generally at 54. As explained earlier, the filled pouches, which issue from the pouch filling machines 1 and 2, are advanced by the check weighers 13 and 14 to the receiving end 55 (FIGURE 5) of the belt conveyor 40 by means of a suitable conveying apparatus (not shown in detail) which is indicated diagrammatically at 56.

The belt conveyor 40 comprises a pair of parallel belt runs 57-57 spaced apart from one another (FIGURES 4 and 9) arranged to support the opposite side portions of the pouches 8 with the hold-back fingers 42 of the hold-back conveyor 41 interposed between the spaced belts to engage the leading edges of the pouches. As best shown in FIGURE 6, the belts are driven by the pulleys 58-58 keyed to the cross shaft 46, which, as noted earlier, is journaled in the conveyor frame 47 and driven by the chain 44 from drive shaft 20.

The opposite end of the belt loops 57-57 are trained about the idler pulleys 60-60 (FIGURES 4 and 5), which are mounted upon an idler shaft 61, also journaled in the frame 47. The frame includes respective adjustment devices 62-62 (FIGURES 3 and 4) engaging the idler shaft 61 for controlling the tension of the belts 57-57. The frame 47 of the timing apparatus is supported by the standards 63-63 (FIGURE 2), which rest upon the floor.

The hold-back conveyor 41, which is mounted above the spaced conveyor belts 57, is supported by the bearing plates, previously indicated at 52-52 at its downstream end and by a pair of similar bearing plates 64-64 (FIGURES 2-4) at its upstream end, the bearing plates being attached to the frame 47 at opposite sides. The structure further includes a series of vertical bars 65 (FIGURES 3-5 and 9) which support the chain loop 66 of the hold-back conveyor 41.

In general, the hold-back conveyor 41 comprises the single chain loop 66 (FIGURES 3-6) having its forward end trained about the drive sprocket 67 of cross shaft 51 journaled in the bearing plates 52-52. As noted earlier, the cross shaft 51 is driven in time with the machine components by the sprocket chain 44 which is connected to the main drive shaft 20.

The downstream end of chain loop 66 passes around an idler sprocket 68 (FIGURE 5) mounted upon an idler shaft 70 journaled in the bearing plates 64-64. As best shown in FIGURE 3, the bearing plates 64-64 each include an adjustment device 71 engaging the opposite ends of idler shaft 70 to regulate the tension of chain loop 66.

As viewed in FIGURES 5 and 9, the upper run of the chain loop 66 is supported by a rail 72 mounted upon a series of cross members 73 extending between the vertical bars 65-65. The lower run of the chain loop 66 is similarly supported upon a rail 74 mounted upon the lower cross members 75.

The pusher fingers 42 of the hold-back conveyor 41 are generally triangular as viewed from the side (FIGURE 5), each finger being pivotally connected as at 76 to the chain loop 66. As explained later with reference to FIGURE 11, the pusher fingers 42 are arranged to pivot upwardly, if necessary, as they advance along the lower run of the chain loop 66. The purpose of this arrangement is to prevent damage to the pouches 8 in the event that a pouch accidentally is advanced by the belt conveyor 40 in a position in which the pusher finger 42 engages the top of the pouch, as shown in FIGURE 11.

In order to permit upward swinging motion of the hold-back fingers 42, each finger (FIGURES 5 and 6) includes an arcuate slot 77 formed in its swinging portion and traversed by a screw 78 passing through the chain loop 66. As viewed in FIGURES 6 and 9, the trailing or heel portion 80 of each finger 42, which includes the slot 77, slides upon the upper rail 72 as the finger passes along the upper run of the chain loop 66, thus holding the fingers in the upright position illustrated. For this purpose, the rail 72 projects laterally from the chain loop 66, as shown in FIGURE 9.

In order to permit the hold-back fingers 42 to pivot upwardly (FIGURE 9) along the lower run of chain loop 66, the lower guide rail 74 does not extend transversely from the chain loop 66. As a consequence, each finger 42 depends by gravity from the lower chain run and is adapted to be rotated about its pivot point 76 in an upward and rearward direction upon encountering an obstruction, as indicated by the arrow in FIGURE 11. However, the slot 77 and screw 78 prevents the finger from being pivoted in the opposite direction, such that the finger resists the forward pressure imposed upon it by the article which is being advanced against the finger by the belt conveyor 40.

As the pouches 8 are transferred from the conveyor 56 of the pouch filling machine (FIGURE 5), the opposite end portions of the pouches rest upon the belt runs 57-57 (FIGURE 9). As explained earlier, the belt runs advance at a rate faster than the hold-back fingers, such that the leading edge of the pouch is intercepted by an advancing hold-back finger 42 which projects downwardly between the belts. As shown in FIGURE 9, the pouches 8 are confined upon the conveyor belt runs 57-57 by the guide rails 81-81 which are mounted upon the frame 47 along opposite sides of the belt runs.

In order to control the spacing of the pouches 8 as they advance from the conveyor 56 of the check weigher, each timing apparatus 3 includes the arresting device 54, comprising a vertically shiftable pouch arresting plate indicated generally at 82 (FIGURE 5). The arresting plate 82 is mounted upon a piston rod 83 projecting upwardly from a piston confined in an air cylinder 84. The lower end of the air cylinder 84 is mounted upon a plate 85 secured to an angle iron 86 which extends transversely across the frame 47 of the timing apparatus. The upper surface of the arresting plate 82 includes a pad 87, formed of foam rubber or the like, which is arranged to establish a frictional engagement with a pouch when the arresting plate 82 is elevated.

As best shown in FIGURE 4, the arresting plate has a width dimension less than the spacing between the belt runs 57 to permit the plate to be shifted by its cylinder 84 to a position above the plane of the belt runs to arrest temporarily any selected pouch, as indicated in FIGURE 14, thereby to time the pouches with respect to the advancing hold-back fingers 4. The arresting plate 82 of each timing apparatus normally resides in a plane spaced below the top surface of the belt conveyor 40 so as to offer no interference with the advancement of normally spaced pouches.

Photoelectric Apparatus

The operation of each arresting plate 82 is regulated by a respective pair of photoelectric cells 88-88 (FIG-

URE 5) which are mounted on a bracket 90 projecting outwardly from one of the bearing plates 64 of the hold-back conveyor 41. As shown in FIGURE 4, the bracket 90 includes a pair of lateral arms 91 arranged to support the photoelectric cells in a centered position above the spaced belt runs 57-57 of the belt conveyor 40.

The apparatus includes a pair of lamps or light sources 92-92 (FIGURE 5) adapted to project respective light beams upwardly to the photoelectric cells 88. The light sources are mounted upon respective brackets 93-93 projecting outwardly from the lower portion of the frame 47. The light sources 92 are also mounted between the belt runs 57 and in vertical alignment with the photoelectric cells so that each lamp 92 projects a light beam upwardly between the spaced belts to its coaxing phototube, as indicated diagrammatically at 94 (FIGURE 5). As explained later, the photoelectric cells 88 are interconnected in a suitable amplifying circuit to regulate the operation of the air cylinder 84 of the arresting plate 82. 20 It will be understood that the light beams 94 are interrupted by the pouches 8 as they advance along the belt runs 57 (FIGURE 5). However, if the successive pouches are located at the proper spacing along the belt runs 57 (conveyor 40), then the arresting plate 82 remains in its lowered, inactive position. In other words, the spacing of the light beams 94 is greater than the length of the pouches; therefore, any given pouch sequentially interrupts the first beam which is indicated at A, then interrupts the next beam, indicated at B, but does not interrupt both beams at the same time. In the present example, the light beams are spaced apart from one another a distance of $6\frac{1}{2}$ " as indicated at C, while the length of the pouch is 6", as indicated at D. The photo cells 88-88 are connected in series in the control circuit and the control circuit is arranged to elevate the arresting plate only if both light beams are interrupted at the same time. As explained later, this action causes the arresting plate to delay the trailing pouch until proper spacing is obtained between the two pouches.

40 FIGURES 13 and 14 illustrate a condition wherein a pouch E issues from the pouch filling mechanism (conveyor 56) in overlapping relationship with a previously issued pouch F. In this example, the pouch F intercepts the light beam B of one photoelectric cell and the pouch E intercepts the beam A. Accordingly, both light beams are interrupted at the same time, thus conditioning the control circuit to elevate the arresting plate 82 (FIGURE 14), thereby to halt the pouch E temporarily.

After the trailing end of pouch F passes beyond the 50 light beam B (FIGURE 14), the circuit is conditioned to lower the arresting plate since only one of the beams (beam A) is now interrupted. The pouch E is thus replaced on the conveyor belts 57 when the normal spacing, indicated at G (FIGURE 15), is restored between the 55 pouches. This spacing corresponds generally with the spacing of the fingers 42 of the hold-back conveyor 41, as noted earlier. By virtue of the fact that the belt runs 57 advance at a rate faster than the hold-back conveyor 41 (fingers 42), pouch F will advance into engagement with the hold-back finger H (FIGURE 15), while the released pouch E will advance into engagement with the next hold-back finger J after it passes around the idler sprocket, as indicated.

60 In the example illustrated in FIGURES 16 and 17, the pouch filling mechanism (conveyor 56) has advanced a pouch K to the belt runs 57 too quickly, such that the spacing L between the pouches K and M is less than the normal spacing, previously indicated at G (FIGURE 15). Without the photoelectric apparatus, the pouch M would advance into engagement with the hold-back finger N and hold-back finger O would engage the top surface of the pouch K, thus disrupting the machine operation. It will be noted in this case, that the two pouches also intercept the light beams A and B at the same time, again causing the control circuit to elevate the arresting plate

82 (FIGURE 17), thereby to arrest pouch K. After the leading pouch M advances beyond the beam B, the circuit will lower the arresting plate, allowing the pouch K to follow the pouch M at the normal spacing, previously indicated at G in FIGURES 15 and 17, thereby to time pouch K with respect to the hold-back finger O.

Infeed Conveyor

As noted above (FIGURES 1 and 6), the pouches 8 are advanced from the downstream end of the timing apparatus 3 to the infeed conveyor 15 to be delivered at proper spacing to the sweep mechanism 17 of each of the pouch fillers 1 and 2. The infeed conveyor 15 of each filler is driven in time with the other components of the machine by means of the common drive shaft 20 and sprocket chain 44, as noted earlier with reference to FIGURE 10.

Described in detail (FIGURE 7), the infeed conveyor chain loop, previously indicated at 37, is trained around the driving sprocket 36 of shaft 34. The opposite end of chain loop 37 is trained around an idler sprocket 95 (FIGURE 6), which is mounted upon a cross shaft 96, also journaled in the side members of frame 47. As shown in FIGURE 6, chain loop 37 is mounted below the chain loop 66 of the hold-back conveyor and its downstream portion (loop 37) overlaps the upstream portion of the hold-back chain 66 and its belt runs 57-57.

By virtue of this arrangement (FIGURE 6) the trailing edge of each pouch 8 is engaged by the disappearing pusher fingers 38 and, at about the same time, the leading edge of the pouch is released by the hold-back fingers 42. Thus as shown in FIGURE 6, the pouch 8 is advanced by the belt conveyor 40 with its leading edge engaged against the advancing hold-back finger, which is indicated at P. At about the time the hold-back finger P swings upwardly about the sprocket 67, the pusher finger Q springs upwardly about the idler sprocket 95 in a position slightly spaced behind the trailing edge of the pouch 8. Thus, the pouch may pause momentarily upon reaching the end of the belt conveyor 40, then its advancement is continued by operation of the pusher finger Q.

As best shown in FIGURE 9, the pusher fingers 38 are arranged in pairs spaced laterally from one another and straddling the hold-back fingers 42, such that there is no possibility of interference between the coacting sets of fingers in the overlapping portion of the two conveyors. The guide rails, previously indicated at 81-81, extend without interruption from the belt conveyor 40 and along the infeed pusher conveyor 15 to the sweep mechanism, in order to hold the advancing pouches properly in alignment with respect to the infeed conveyor.

As shown in FIGURE 6, the pusher fingers 38-38 are pivotally mounted upon opposite end portions respective pivot pins 99 which pass through the chain 37, with the fingers located on opposite sides of the chain. Each pusher finger includes a tailpiece 97; the tailpieces slide upon the upper surface of respective tailpiece rails 98 extending along opposite sides of the upper run of chain 37 (FIGURE 8). The rails 98 thus hold the fingers 38 in the upright position as they push the pouches 8 along the upper run of the infeed conveyor 15 toward the sweep mechanism. The upper run of each chain loop 37 is supported by a chain rail 101 (FIGURE 8) which is interposed between the rails 98-98.

As the pouches are advanced along the infeed conveyor 15, the opposite end portions of the pouches are supported upon spaced article support rails 102-102 (FIGURE 8) which are spaced above the rails 98 and 101. The articles support rails 102 (FIGURE 6) extend from the upstream idler pulley 58 of the belt conveyor 40, such that the pouches are transferred without interference from the belt conveyor to the article support rails 102.

In order to prevent the pusher fingers 38 from pivoting

in the forward direction along the upstream conveyor run, the chain 37 is provided with cross pins 103 which project outwardly from opposite sides of the chain and overlie the upper surface of each tailpiece 97, such that each tailpiece is confined between its rail 98 and cross pin 103 along the upper run. As viewed in FIGURE 7, the end portion of the tailpiece rails 98-98 straddle the drive sprocket 36 and their end portions are curved downwardly as at 104 about a radius common to the axis of the sprocket 36. The pusher fingers 38 are thus free to pivot by gravity toward the chain run as they pass about the idler sprocket 95 (FIGURE 6) as indicated at 105 in broken lines in this view. When the tailpiece engages the upstream end 106 of the tailpiece rail 98, the finger is pivoted abruptly by the rail to its operating position into engagement with the trailing edge of the pouch.

Again referring to FIGURE 7, the portions of the article support rails 102, which extend beyond the sprocket 36 are inclined downwardly as at 107. The lower end of the downwardly inclined portions 107 are connected to the dead plate 16, which is mounted directly above the bucket conveyor 5. The rate of advancement of the infeed conveyor 15 is sufficient to propel the pouches against the stop 108 which is mounted along one edge of the dead plate. As explained earlier, the apparatus is timed to feed two pouches, one above the other, to the dead plate, then the sweep mechanism 17 transfers the two pouches to the appropriate conveyor bucket. In order to permit the second pouch R to be placed upon the lower pouch S, the dead plate 16 is in the form of a pocket, one end of which is delineated by the curved section 110 extending from the downwardly inclined rail portion 107. The opposite end of the pocket is delineated by the stop 108. After being transferred to the dead plate, the superposed pouches R and S dwell momentarily, then they are transferred by the sweep fingers 30 of the sweep mechanism 17 into the advancing conveyor bucket.

Sweep Mechanism

As described earlier with reference to FIGURES 2, 7 and 10, each sweep mechanism 17 is driven in time with the several components of the machine by way of the main shaft 20, cross shaft 23, and sprocket chain 26, which drives the power shaft 28 of the sweep mechanism. The driving system advances the sweep fingers 30 of each sweep mechanism at a linear rate corresponding to the advancement of the buckets 4 of the bucket conveyor 5. However, the sweep fingers, of each sweep mechanism, in the present example, are spaced apart from one another to advance in time with the alternate buckets of the conveyor. Thus, as noted earlier, the sweep mechanism of the downstream pouch filler 1 transfers one pair of pouches R and S from its dead plate into a given conveyor bucket and skips each alternate bucket. A similar pair of superposed pouches T and U are transferred into the alternate empty buckets as they advance relative to the sweep mechanism of the upstream filler mechanism 2.

Described in detail with reference to FIGURES 2, 7 and 10, which represent the downstream sweep mechanism, the power shaft 28 of the sweep mechanism has its opposite ends rotatably journaled in the spaced side plates of the frame 24 of the bucket conveyor. Respective laterally spaced sprockets 111-111 are keyed to the power shaft 28 between the side plates of the conveyor frame, each sprocket including a respective chain loop 112. The opposite ends of the chain loops 112-112 (FIGURE 10) pass around respective idler sprockets 113-113 which are mounted upon an idler shaft 114, also having its opposite ends journaled in the side plates of the frame 24.

The chain loops 112-112 include a cross piece 109 extending transversely between the chain loops 112 and having their opposite ends connected to the chains by brackets 115-115 (FIGURE 7). The sweep fingers, previously indicated at 30, project downwardly in pairs

from each crosspiece 109. The arrangement is such that the sweep fingers along the lower run of the chain loops 112 pass across the dead plate 16 in registry with the trailing edge of related conveyor bucket 4 at the same rate of advancement.

The spacing of the sweep fingers is such that respective pairs of sweep fingers of each sweep mechanism 17 register with alternate buckets 4 of the conveyor 5, as noted above. The lower ends of the sweep fingers 30 are spaced slightly above the top surface of the dead plate 16 as at 116 (FIGURE 7) such that the fingers engage both superposed pouches 8 which rest upon the dead plate. As the fingers 30 advance across the dead plate, the superposed pouches drop by gravity into the related conveyor bucket 4 for advancement toward the cartoning machine. As explained earlier, the two sweep mechanisms thus load the alternate buckets of the conveyor 5 for advancement of the pouches to the cartoning machine 6.

Control System

The electrical control circuit (FIGURE 18) which operates the arresting plates 82—82 in response to the advancement of the pouches 8, is conventional and is not disclosed in detail. In general, the system includes an amplifying circuit interconnected with the photoelectric cells 88 and adapted to operate the arresting plates in response to the signals from the cells. As noted earlier, the light beams 94 of each timing mechanism are interrupted by the pouches which are advanced from the filling mechanism to the belt conveyor 40 (FIGURE 5). When the light beams of the related pair of photocells are interrupted individually by the normally spaced pouches 8, the control system causes the arresting plate of that pair to remain in its normal lowered position. However, when the pouches are improperly spaced (FIGURES 13-17) causing both light beams of a given pair to be interrupted at the same time, then the control system elevates the arresting plate to restrain the trailing pouch until the normal spacing between the pouches is reestablished.

As shown generally in FIGURE 18, the control system is energized by the power lines 117 which are connected to the respective pairs of lamps 92—92 by the branch lines 118—118. The power lines 117 also energize the amplifying circuit 120, which is of conventional design. The amplifying circuit includes the necessary amplifying tubes and coating transformers and rectifiers for operating the tubes.

The pairs of photoelectric cells 88 are connected to the amplifying circuit by way of the pairs of output lines which transmit the signals from the cells to the amplifying circuit. Thus, the branch lines 121 and 122 interconnect the cells 88 of the downstream timing apparatus with the amplifying circuit 120, while the branch lines 123 and 124 interconnect the cells of the upstream apparatus with the amplifying circuit.

It will be recalled that the respective arresting plates 82, normally reside in their lowered position and are shifted to the elevated arresting position by the respective air cylinders 84. Operation of these cylinders is regulated by respective electrical reversing valves 125. An air line 126 supplies air pressure to the electrically operated valves 125 by way of the branch lines 127—127. Air pressure is transmitted to the cylinders 84 by branch lines 128 and 130 which lead from the reversing valves 125 to the opposite ends of the cylinders 84—84.

During normal operation of either timing apparatus, with the pouches properly spaced, the amplifying circuit 120 conditions the related electrically operated valves 125 to supply air pressure by way of the conduit 128 to the upper portion of the cylinder 84. In this valve position, the conduit 130 exhausts through the valve to the atmosphere, thus holding the arresting plate in its lowered position. However, when both light beams 94

of a given pair are interrupted concurrently by overlapping or improperly spaced pouches, then the related cells signal the amplifying circuit by way of lines 121 and 122 or lines 123 and 124 to energize the related reversing valve 125. In response to this signal, the amplifying circuit energizes the power lines 131—131 or 132—132 leading to the electrically operated valve of that timing apparatus.

Upon being energized, the electrically operated valve 125 transmits air pressure from air line 126 by way of the conduit 130 to the lower end of the cylinder. The valve also opens the upper conduit 128 to the atmosphere, causing the piston of that cylinder to elevate the arresting plate 82. As soon as normal pouch spacing is restored, with only one of the light beams interrupted, the amplifying circuit shifts the reversing valve back to its normal position so as to lower the arresting plate for normal advancement of the pouches.

Having described my invention I claim:

1. In a mechanism for receiving articles which issue from a machine at random and for advancing said articles at a substantially uniform normal spacing, a belt type article conveyor adapted to receive successive articles delivered from the said machine and to frictionally engage and advance the articles at said random spacing, a hold-back conveyor mounted relative to the article conveyor, said hold-back conveyor advancing in the same direction and at a rate slower than the articles conveyor, said hold-back conveyor having hold-back elements adapted to intercept and restrain the articles which are frictionally transported on the belt type article conveyor, a photoelectric apparatus mounted relative to said article conveyor and adapted to respond to the advancement of the articles at random spacing along the article conveyor, said photoelectric apparatus including an arresting device operating in response to the photoelectric apparatus and adapted to arrest a trailing article on the article conveyor which is located at less than the normal spacing relative to an adjacent leading article, said arresting device adapted to release the arrested article in response to operation of the photoelectric apparatus when the normal spacing thereof relative to the adjacent leading article is reestablished, whereby said articles are advanced into engagement with the hold-back conveyor at substantially uniform spacing.

2. In a mechanism for receiving articles which issue at random spacing from a processing machine and for advancing said articles at a substantially uniform normal spacing, a belt type article conveyor adapted to receive and advance the successive articles in spaced relationship to one another, a hold-back conveyor mounted relative to the article conveyor and adapted to advance in the same direction and at a rate less than the rate of advancement of the article conveyor, said hold-back conveyor having hold-back elements mounted thereon at uniform spacing, said hold-back elements adapted to intercept and restrain the articles which are transported upon the belt type article conveyor, thereby to advance the articles at uniform spacing corresponding to the spacing of said hold-back elements, and a photoelectric apparatus mounted relative to said belt type article conveyor at a point upstream from the hold-back conveyor and adapted to respond to the random advancement of the articles along the article conveyor, said photoelectric apparatus including an arresting device, said arresting device, in response to operation of the photoelectric apparatus, adapted to engage and lift an article from the article conveyor which is located relative to an adjacent article at a spacing less than the spacing of said hold-back elements, thereby to arrest said article, said arresting device adapted to lower said arrested article into engagement with the article conveyor in response to operation of the photoelectric apparatus when the normal spacing thereof relative to the adjacent article is reestablished, whereby said articles are advanced along said

article conveyor beyond said photoelectric apparatus at a spacing which corresponds generally to the spacing of the hold-back elements, of the hold-back conveyor.

3. In a mechanism for receiving articles which issue at random spacing from a processing machine and for advancing said articles at a substantially uniform normal spacing, a belt type article conveyor adapted to receive and advance the successive articles in spaced relationship to one another, a hold-back conveyor mounted relative to the article conveyor and adapted to advance in the same direction and at a rate less than the rate of advancement of the article conveyor, said hold-back conveyor having hold-back elements mounted thereon at uniform spacing, said hold-back elements adapted to intercept restrain the articles which are transported upon the belt type article conveyor, thereby to advance the articles at uniform spacing corresponding to the spacing of said hold-back elements, and a photoelectric apparatus mounted relative to said belt type article conveyor at a point downstream from the hold-back conveyor and adapted to respond to the random advancement of the articles along the article conveyor, said photoelectric apparatus including an arresting element which is responsive to operation of the said photoelectric apparatus, said arresting element adapted to engage and lift an article from the article conveyor which is located relative to an adjacent article at a spacing less than the spacing of said hold-back elements, thereby to arrest said article, said arresting element adapted to lower the arrested article into engagement with the article conveyor in response to operation of the photoelectric apparatus, thereby to release said arrested article when the normal spacing thereof relative to the adjacent article is reestablished, whereby said articles are advanced along said article conveyor beyond said photoelectric apparatus at a spacing which corresponds generally to the spacing of said hold-back elements, said articles being advanced individually by the said article conveyor into engagement with the trailing edge of respective hold-back elements, said hold-back conveyor being adapted to restrain the articles at substantially uniform spacing as the articles are advanced by the article conveyor.

4. In a mechanism for receiving articles which issue at random spacing from a processing machine and for advancing said articles at a substantially uniform normal spacing, a belt type article conveyor adapted to receive and advance the successive articles in spaced relationship to one another, a hold-back conveyor mounted relative to the article conveyor and adapted to advance in the same direction and at a rate less than the rate of advancement of the article conveyor, said hold-back conveyor having hold-back elements pivotally mounted thereon at uniform spacing, said hold-back elements adapted to swing to an inactive retracted position in the direction of advancement of the article conveyor, said hold-back elements adapted to intercept and restrain the articles which are transported upon the belt type article conveyor, thereby to advance the articles at uniform spacing corresponding to the spacing of said hold-back elements, and a photoelectric apparatus mounted relative to said belt type article conveyor at a point downstream from the hold-back conveyor and adapted to respond to the random advancement of the articles along the article conveyor, said photoelectric apparatus including an arresting element which is responsive to operation of the photoelectric apparatus, said arresting element adapted to engage and lift an article from the article conveyor which is located relative to an adjacent article at a spacing less than the spacing of said hold-back elements, thereby to arrest said article, said arresting element adapted to lower said arrested article into engagement with the article conveyor in response to operation of the photoelectric apparatus, thereby to release said arrested article when the normal spacing thereof relative to the adjacent article is reestablished, whereby said articles are advanced

along said article conveyor beyond said photoelectric apparatus at a spacing which corresponds generally to the spacing of the hold-back elements, said hold-back elements adapted to swing to said inactive retracted position upon engaging the top surface of an article on said article conveyor, whereby the article is advanced by the article conveyor to a successive hold-back element.

5. In a mechanism for receiving articles which issue from a machine at random and for advancing said articles at a substantially uniform normal spacing, a belt type article conveyor adapted to receive successive articles delivered from the said machine and to frictionally engage and advance the articles at said random spacing, a hold-back conveyor mounted relative to the article conveyor, said hold-back conveyor advancing at a rate slower than the article conveyor and adapted to intercept and restrain the articles which are frictionally transported on the belt type article conveyor, an article arresting apparatus mounted relative to said article conveyor in a position upstream from the hold-back conveyor and adapted to respond to the advancement of the articles at random spacing along the article conveyor, a photoelectric apparatus mounted relative to said article conveyor and adapted to respond to the advancement of the articles which are advanced a random spacing on the article conveyor, said photoelectric apparatus interconnected with said article arresting apparatus and adapted to actuate the same, said article arresting apparatus, in response to operation of the photoelectric apparatus, adapted to arrest a trailing article on the article conveyor which is located at less than the normal spacing relative to an adjacent leading article and to release the arrested article when the normal spacing thereof relative to the adjacent leading article is reestablished, whereby said articles are advanced into engagement with the hold-back conveyor at substantially uniform spacing.

6. In a mechanism for receiving articles which issue at random spacing from a processing machine and for advancing said articles at a substantially uniform normal spacing, a belt type article conveyor adapted to receive and advance the successive articles in spaced relationship to one another, a hold-back conveyor mounted relative to the article conveyor and adapted to advance in the same direction at a rate less than the rate of advancement of the article conveyor, said hold-back conveyor having hold-back elements mounted thereon at uniform spacing, said hold-back elements adapted to intercept and restrain the articles which are transported upon the belt type article conveyor, thereby to advance the articles at uniform spacing corresponding to the spacing of said hold-back elements, and a photoelectric article arresting apparatus mounted relative to said belt type article conveyor at a point upstream from the hold-back conveyor, said photoelectric arresting apparatus adapted to respond to the random advancement of the articles along the article conveyor, said article arresting apparatus including shiftable means responsive to operation of the photoelectric article arresting apparatus and adapted to arrest an article on the article conveyor which is located relative to an adjacent leading article at a spacing less than the spacing of said hold-back elements, said shiftable means being responsive to the photoelectric arresting apparatus and adapted to be shifted to a release position, thereby to release said arrested article when the normal spacing thereof relative to the adjacent leading article is reestablished, whereby said articles are advanced along said article conveyor beyond said photoelectric article arresting apparatus at a spacing which corresponds generally to the spacing of the hold-back elements of the hold-back conveyor, adapting the article conveyor to advance the articles into engagement with the trailing sides of the hold-back elements.

7. In a mechanism for receiving articles which issue at random spacing from a processing machine and for advancing said articles at a substantially uniform spacing,

an article conveyor comprising a pair of spaced parallel belts adapted to receive the opposite end portions of the articles and to advance the same, a hold-back conveyor mounted above said article conveyor and adapted to advance at a rate less than the rate of advancement of the article conveyor, said hold-back conveyor having hold-back elements mounted at a normal uniform spacing, said hold-back elements projecting downwardly relative to the spaced belts of the article conveyor and adapted to engage and restrain the articles which are transported upon the spaced belts of the article conveyor, and photoelectric article arresting means mounted relative to said belt type article conveyor at a point upstream from the hold-back conveyor, said photoelectric article arresting means adapted to respond to the random advancement of the articles along the article conveyor, said photoelectric article arresting means including a shifting element adapted to arrest an article on the article conveyor which is located relative to an adjacent article at a spacing less than the spacing of said hold-back elements of the hold-back conveyor, said shiftable element of the photoelectric article arresting means adapted to release said arrested article when the normal spacing thereof relative to the adjacent article is reestablished, whereby said articles are advanced along said article conveyor beyond said arresting means at a spacing which corresponds generally to the spacing of said hold-back elements.

8. In a mechanism for receiving articles which issue at random spacing from a processing machine and for advancing said articles at a substantially uniform spacing, an article conveyor comprising a pair of spaced parallel belts adapted to receive the opposite end portions of the articles and to advance the said articles, a hold-back conveyor mounted above said article conveyor and adapted to advance at a rate less than the rate of advancement of the article conveyor, said hold-back conveyor having hold-back elements mounted at a normal uniform spacing, said hold-back elements projecting downwardly relative to the spaced belts of the article conveyor, said hold-back elements adapted to engage and restrain the articles which are transported upon the spaced belts of the article conveyor, and article arresting means mounted relative to said belt type article conveyor at a point upstream from the hold-back conveyor, said arresting means adapted to respond to the random advancement of the articles along the article conveyor, said article arresting means including an arresting element interposed between the spaced parallel belts of the article conveyor and normally residing in an inactive position relative to said belts, said arresting means adapted to shift said article arresting element to an active position relative to the belts of the article conveyor in response to the advancement of an article on the article conveyor which is located relative to an adjacent article at a spacing less than the spacing of said hold-back elements of the hold-back conveyor, said arresting means adapted to shift said arresting element back to said inactive position and to release said trailing article when the normal spacing thereof relative to the adjacent article is reestablished, whereby said articles are advanced along said article conveyor beyond said arresting means at a spacing which corresponds generally to the spacing of said hold-back elements.

9. A mechanism for receiving articles which issue at random spacing from a processing machine and for transferring said articles to a cartoning machine conveyor at substantially uniform spacing in time with the cartoning machine conveyor, said mechanism comprising, an article conveyor adapted to receive said articles at random spacing, an article arresting mechanism adapted to operate in response to the advancing articles on the article conveyor, said arresting mechanism adapted to arrest an article which is disposed at less than a normal spacing relative to an adjacent article and to release said article when a normal spacing is reestablished, a hold-back conveyor mounted relative to the article conveyor and advancing

at a rate slower than the article conveyor, said hold-back conveyor adapted to engage and restrain the normally spaced articles on the article conveyor downstream from the arresting mechanism, and a sweep mechanism mounted relative to the cartoning machine conveyor and adapted to receive the spaced articles advanced from the hold-back conveyor, said sweep mechanism having a sweep element advancing in the same direction as the cartoning machine conveyor and at the same rate of speed, said sweep element adapted to engage and transfer the article from the sweep mechanism to the cartoning machine conveyor in time with the advancement thereof.

10. A timing mechanism for receiving articles which issue at random spacing from a processing machine and for transferring said articles to the buckets of a cartoning machine conveyor in time with the advancement of the cartoning machine conveyor, said cartoning machine conveyor being disposed substantially at right angles to the timing mechanism, said timing mechanism comprising a belt conveyor adapted to receive said articles at random spacing, an article timing mechanism mounted adjacent the belt conveyor, and adapted to space the articles uniformly on the belt conveyor, a holdback conveyor mounted relative to the belt conveyor and advancing at a rate slower than the belt conveyor, said holdback conveyor adapted to engage and restrain the normally spaced articles on the belt conveyor downstream from the timing mechanism, a dead plate mounted above the cartoning machine conveyor and adapted to receive the articles advanced from the hold-back conveyor, and a sweep mechanism mounted above said dead plate and having a sweep element adapted to pass across the dead plate in the same direction as the cartoning machine conveyor and at the same rate of speed, said sweep element adapted to engage an article resting upon the dead plate and to transfer the article from the dead plate into a bucket of the cartoning machine conveyor.

11. A timing mechanism for receiving articles which issue at random spacing from a processing machine and for transferring said articles to the buckets of a cartoning machine conveyor in time with the cartoning machine conveyor, said cartoning machine conveyor being disposed substantially at right angles to the timing mechanism, said timing mechanism comprising, a belt conveyor adapted to receive said articles at random spacing, an article timing mechanism mounted adjacent the belt conveyor and adapted to space the articles uniformly on the belt conveyor, a hold-back conveyor mounted relative to the belt conveyor and advancing at a rate slower than the belt conveyor, said hold-back conveyor adapted to engage and restrain the normally spaced articles on the belt conveyor downstream from the timing mechanism, an infeed conveyor mounted downstream from the hold-back conveyor and adapted to engage the trailing edges of the normally spaced articles at the downstream end of the hold-back conveyor, a dead plate mounted at the downstream end of the infeed conveyor above the cartoning machine conveyor and adapted to receive the articles advanced by the infeed conveyor, and a sweep mechanism mounted above said dead plate and having a sweep element adapted to pass across the dead plate in the same direction as the cartoning machine conveyor and at the same rate of speed, said sweep element adapted to engage the article resting upon the dead plate and to transfer the article from the dead plate into a bucket of the cartoning machine conveyor.

12. A timing mechanism for receiving articles which issue at random spacing from a processing machine and for transferring said articles to the buckets of a cartoning machine conveyor in time with the cartoning machine conveyor, said cartoning machine conveyor being disposed substantially at right angles to the timing mechanism, said timing mechanism comprising, a belt conveyor adapted to receive said articles at random spacing, an

article timing mechanism mounted adjacent the belt conveyor and adapted to locate the article at substantially uniform spacing on the belt conveyor, a hold-back conveyor mounted relative to the belt conveyor and advancing at a rate slower than the belt conveyor, said hold-back conveyor having spaced hold-back fingers adapted to swing to an inactive position upon engaging the upper surface of an article resting on the belt conveyor, said fingers adapted to engage and restrain the normally spaced articles on the belt conveyor downstream from the timing mechanism, a dead plate mounted at the downstream end of the infeed conveyor above the cartoning machine conveyor and adapted to receive the articles advanced from the hold-back conveyor, and a sweep mechanism mounted above said dead plate and having a sweep element adapted to pass across the dead plate in the same direction as the cartoning machine conveyor and at the same rate of speed, said sweep element adapted to engage an article resting upon the dead plate and to transfer the article from the dead plate into a bucket of the cartoning machine conveyor.

13. In a mechanism for receiving articles which issue at random spacing from a processing machine and for advancing said articles at substantially uniform spacing, an article conveyor, a photoelectric apparatus mounted relative to said article conveyor, said photoelectric apparatus comprising a plurality of light sources and related photoelectric cells arranged to receive light beams from the light sources, said cells and related photoelectric cells and being spaced longitudinally from one another along the article conveyor, whereby articles advancing along the article conveyor interrupt said light beams, an article arresting element mounted relative to the article conveyor, said arresting element normally residing in an inactive position and adapted to be shifted to an active position, thereby to arrest an article advancing along said article conveyor, a control system interconnected with the photoelectric cells and adapted to shift said article arresting element from the inactive to the active position in response to a signal from the control system, said control system adapted to transmit a signal and to cause the arresting element to be shifted to an active position upon concurrent interruption of said light beams by said articles, whereby the arresting element arrests an article which is located relative to an adjacent article at a spacing less than a normal spacing, and a hold-back conveyor mounted relative to the article conveyor in a position downstream from the article arresting element and advancing at a rate slower than the article conveyor, said hold-back conveyor adapted to engage and restrain the normally spaced articles advancing along the article conveyor downstream from said article arresting element.

14. In a mechanism for receiving articles which issue at random spacing from a processing machine and for advancing said articles at substantially uniform spacing, an article conveyor, a photoelectric apparatus mounted relative to said article conveyor, said photoelectric apparatus comprising a pair of light sources mounted in positions to project respective light beams relative to the article conveyor, a pair of photoelectric cells mounted in positions to receive the light beams projected from the light sources, an article arresting element mounted relative to the article conveyor, said arresting element normally residing in an inactive position and adapted to be shifted to an active position, thereby to arrest an article advancing along the article conveyor, a control system interconnected with the photoelectric cells and adapted to shift said article arresting element from

5 the inactive to the active position in response to a signal from the said control system, said photoelectric cells and related light sources being located along the article conveyor at a spacing whereby said light beams are intercepted individually by the articles which advance at a normal spacing along the belt conveyor and are intercepted concurrently by articles which advance along the belt conveyor at less than said normal spacing, said control system adapted to transmit said signal and thereby to shift the arresting element to the active position upon concurrent interruption of both of said light beams by said articles, whereby the arresting element arrests the article which is located relative to an adjacent article at a spacing less than said normal spacing, and a hold-back conveyor mounted relative to the article conveyor in a position downstream from the arresting element and advancing at a rate slower than the article conveyor, said hold-back conveyor adapted to engage and restrain the normally spaced articles advancing along the article conveyor downstream from said article arresting element, thereby to preserve the spacing which is imparted to the articles by said article arresting element.

15. In a mechanism for receiving articles which issue at random spacing from a processing machine and for advancing said articles at substantially uniform spacing, 25 an article conveyor, a photoelectric apparatus mounted relative to said article conveyor, said photoelectric apparatus comprising a pair of light sources mounted in positions to project respective light beams relative to the article conveyor, a pair of photoelectric cells, mounted in position to receive the light beams projected from the light sources, an article arresting element mounted relative to the article conveyor, said arresting element normally residing in an inactive position and adapted to be shifted to an active position, thereby to arrest an article advancing along the article conveyor, a control system interconnected with the photoelectric cells and adapted to shift said article arresting element from the inactive to the active position in response to a signal from the 30 said control system, said photoelectric cells and related light sources being spaced apart along the belt conveyor at a spacing greater than the length of said articles, whereby said light beams are intercepted individually in sequence by the articles which advance at a normal spacing along the article conveyor, said light beams adapted to be intercepted concurrently by the articles when the articles are advanced along the article conveyor at less than said normal spacing, said control system adapted to transmit said signal and thereby to shift the arresting element to the active position upon concurrent interruption of both of said light beams by said articles, whereby the arresting element arrests the article which is located relative to an adjacent article at a spacing less than said normal spacing, and hold-back means 35 mounted relative to the article conveyor in a position downstream from the arresting element, said hold-back means adapted to engage and restrain the normally spaced articles advancing along the article conveyor downstream from said article arresting element, thereby to preserve the spacing which is imparted to the articles by said article arresting element.
